UNITED STATES PATENT OFFICE.

ISIDOR DRESDNER, OF BROOKLYN, NEW YORK.

FUR-PLUCKING MACHINE.

SPECIFICATION forming part of Letters Patent No. 269,838, dated January 2, 1883.

Application filed September 6, 1882. (No model.)

To all whom it may concern:

Be it known that I, ISIDOR DRESDNER, of Brooklyn, in the county of Kings and State of New York, have invented a new and useful Improvement in Fur-Plucking Machines; and I do hereby declare that the following is a full and exact description thereof, reference being had to the accompanying drawings, and to the letters of reference marked thereon, making a part of this specification.

My invention relates to machinery for removing the master-hairs from pelts; and it has for its object a more perfect, simple, and efficient mechanism for producing expeditiously and neatly the desired result.

It consists mainly in the combination of an oscillating and vertically-reciprocating blade with an elastic roller, so arranged in connection with an endless belt as that the fur-skin being secured upon the belt shall be carried into close proximity to the roller and there doubled or bent back, so as to throw the long stiff master-hairs upon the roller in manner to be caught and held thereon by the edge of the blade until, in the revolution of the roller, they are pulled out from the skin.

It consists, furthermore, in devices for actuating the plucking-blade and for securing the pelt upon the belt, all as hereinafter fully described.

In the accompanying drawings, Figure 1 is an elevation of the rear of my improved fur-plucking machine; Fig. 2, a central longitudinal section thereof; and Fig. 3, a detached view, in perspective, of one of the clamps for securing the pelt upon the endless belt.

The frame of the machine is represented in the drawings by the letters A A', A being the bed, and A' A' uprights at one end thereof, which are connected at the top by a cross-bar, a. Between the uprights an elastic roller, B, is journaled in suitable boxes, C C, which are made to slide vertically in suitable ways formed in the uprights, and are secured when adjusted by means of set-screws, D. The roller is preferably covered with soft rubber, so as to yield slightly under the pressure of the plucking-blade thereon, and is made to revolve with a constant uniform motion from front to rear by any suitable motive power.

The plucking-blade E, made of thin steel, is secured to a bar, F, hinged to a cross-head, G,

which travels freely up and down between the uprights A' A' in suitable ways formed therein or thereon to guide its vertical movements. 55 The blade E is secured to the front face of the bar F, so as to drop parallel with the axis of the roller into contact with its periphery in a plane which will intersect the horizontal plane of the axis about two-thirds of the distance 60 from the center to the circumference of the roller. The upper rear edge of the bar F is hinged to the reciprocating cross-head G, so that when the blade drops into contact with the surface of the roller and, engaging the 65 same, is carried upward by it in its revolution the bar and blade will swing back on its hinges, the cross-head being in the meantime carried up by the movement.

A spring-plate, H, placed over the hinged 70 joint of the blade-bar with the cross-head, serves to throw back the blade into its first position, in readiness to drop vertically upon the roller so soon as, in the revolution of the roller, it reaches its highest point and is released therefrom. The blade is lifted at the proper moment and carried down to re-engage the roller by means of a crank-shaft, J, rotating in bearings in the uprights A' A' over the elastic roller B. The crank-shaft is provided with a 80 central crank, J', to which the cross-head G, carrying the blade-bar F and blade E, is connected by a pitman-rod K. This rod is made in two telescopic sections, and a spring, L, is interposed between the sections, being confined 85 in the recess of the one, so that the end of the other may bear thereon, as illustrated in Fig. 2. The crank-shaft may be either geared to the roller by means of a belt or other form of gearing or independently to the master-shaft. 90

Upon the bed A of the machine, in front of the roller B, is placed a movable stand or frame, M, whose uprights serve to support horizontal rollers N O, placed parallel to each other and to the plucking-roller B, and in the same horizontal plane as the latter. The roller N, placed next to the plucking-roller B, is very small in diameter, while the opposite roller, O, is much larger. Over these rollers is carried an endless belt, P, formed of several layers of soft 100 flexible material, and upon this soft belt the pelt to be plucked is secured by means of clamping-plates R R'. These plates are of a length somewhat greater than the width of the belt,

and are hinged together at one end. The inner face of one of them, R, is fitted with two longitudinal serrated strips, S S, on either edge, whose teeth project upward. The inner face 5 of the opposite plate, R', is fitted with a single central longitudinal serrated strip, S'. The pelt being laid upon the upper face of the endless belt, its ends are secured thereto by passing one of the clamping-plates under and the other 10 over the belt and upon the end of the skin. The free ends of the plate are brought together and secured by means of a ring, T, a screw, or other suitable device. When the clamps are brought together and secured the portion of 15 the pelt under the clamping-plate is, by the pressure of the clamp thereon, so sunken into the soft surface of the belt as that the surface of the plate will not project above the level of the fur, and hence will readily pass between 20 the roller N and the plucking-roller B without interference.

The stand M admits of adjustment to and from the roller B, so as to regulate the interval between said roller and the belt, and is so 25 adjusted by means of a screw, U, working through a standard, V, on the front end of the bed-plate A. This standard V also admits of vertical adjustment, so as to tip the stand M and so throw the forward end of the endless belt 30 nearer or to farther from the plucking-roller. The screw U may be removed and the stand M be kept in position by hand or by the pressure of the operator's body against the front end, in which case a spring, W, which operates 35 to withdraw the stand from the plucking-roller B, is introduced, and the operator actuates said spring in producing the desired adjustment of his endless carrier to the plucking-roller.

40 When the pelt is properly adjusted upon the belt and the machine set in motion the pelt is carried slowly forward, and in passing over the small roller N is so bent and doubled thereon as to throw out the long master-hairs against 45 the face of the elastic roller B. As the long hairs fall upon this roller, the blade E, dropping thereon, will confine them between its edge and the face of the roller, and as the roller and blade revolve from the pelt these hairs are pulled out 50 by the movement. In the revolution of the roller B the blade E is carried upward thereby, any undue strain being taken up by the spring L in the pitman-connection. The blade is also carried back, the hinged joint of its carrying-bar F permitting such a movement; but so 55 soon as the blade has thus moved back into contact with the roller B to pull out the hairs engaged thereby the movement of the crank J' upon the shaft J will operate to lift the blade 60 from the roller. The action of the spring H

will now throw the blade E forward again into its first position, ready in its descent to engage the next series of hairs thrown upon the roller B by the continued movement of the endless belt.

65

Where fine furs—such as seal-skins—are to be plucked, I contemplate attaching a blower to the machine, by means whereby a blast of air will be directed against the pelt as it reaches the plucking-roller, so as to blow back the finer 70 hairs, leaving the stiff master-hairs isolated, and thereby facilitating their engagement by the plucking-blade.

I claim as my invention—

1. The combination, in a fur-plucking machine, of an elastic roller, B, a hinged blade, E, reciprocating to and from the face of the roller, and a small roller or rounded edge, N, placed parallel with the roller B, over which the pelt *x x* to be plucked is carried, substantially in the manner and for the purpose herein set forth.

75

2. The combination, in a fur-plucking machine, with each other and with a crank-shaft, J, of a reciprocating cross-head, G, pitman K, 85 hinged cross-bar E, spring H, plucking-blade E, and plucking-roller B, substantially in the manner and for the purpose herein set forth.

80

3. The combination, with the plucking-roller B, hinged plucking-blade E, reciprocating 90 cross-head G, crank J, and pitman K, of a spring, L, interposed between the pitman and cross-head, substantially in the manner and for the purpose herein set forth.

95

4. The combination, in a fur-plucking machine, with the plucking-roller B and hinged reciprocating plucking-blade E, of the adjustable frame M, adapted to support and hold the pelt to be plucked against said plucking-roller B, substantially in the manner and for the purpose 100 set forth.

100

5. The combination, in a fur-plucking machine, with a plucking-roller, B; and plucking-blade E, and with a suitable supporting frame, M, of an endless belt, P, substantially in the 105 manner and for the purpose herein set forth.

105

6. The combination, in a fur-plucking machine, with an endless belt, P, of serrated clamping-plates adapted to embrace and close upon the opposite sides of the belt, substantially in the manner and for the purpose herein set forth.

110

In testimony whereof I have signed my name to this specification in the presence of two subscribing witnesses.
